UNITED STATES PATENT OFFICE.

HIMAN JACOB, OF NEW YORK, N. Y.

DESIGN FOR A BIFURCATED GARMENT.

SPECIFICATION forming part of Design No. 31,270, dated July 18, 1899.

Application filed June 17, 1899. Serial No. 720,986. Term of patent 7 years.

To all whom it may concern:

Be it known that I, HIMAN JACOB, a citizen of the United States, residing at New York, in the borough of Manhattan and State of New York, have invented and produced a new and original Design for Bifurcated Garments, of which the following is a specification, reference being had to the accompanying drawings, forming part thereof.

10 Figure 1 is a rear elevation of a bifurcated garment, showing my new design. In this view the garment is supposed to be lying down flat, so that the lower ends of the legs of the garment are turned outwardly. Fig. 2 is a 15 similar side elevation of the same.

The leading feature of my design, as shown in the drawings, consists of a row of buttons at each side of the garment, short radial transverse ribs at one side of the buttons and 20 a longitudinal plait at the other side, all arranged at the upper end of the garment, and a row of buttons, short transverse ribs at one side of the buttons and a longitudinal plait at the other side, all arranged at the lower 25 end of each bifurcation or leg of the garment and reversed in position with respect to and arranged approximately in line with the corresponding features at the upper part of the garment.

30 A is the upper or waist portion, and B B

the legs or bifurcations, of the bifurcated garment. At each side of the garment the ornamentation is the same, and consists, at the upper part of the garment, of a longitudinal row of buttons d , transverse ribs d' radiating 35 from the buttons at one side and a longitudinal plait d^2 on the other side of the garment, and, at the lower end of the leg or bifurcation of the garment, of a longitudinal row of buttons e , transverse ribs e' radiating from the 40 buttons at one side and a longitudinal plait e^2 on the other side of the garment, said ornaments or decorations e' and e^2 being reversed with respect to the ornaments or decorations d' and d^2 . The group of decorations or ornaments $e' e' e^2$ are approximately in line with the decorations or ornaments $d d' d^2$. A gathered portion f is at the upper part of the garment.

What I claim is—

50 The design for a bifurcated garment, as shown and described.

In testimony that I claim the foregoing as my invention I have signed my name in presence of two subscribing witnesses.

HIMAN JACOB.
